UNITED STATES PATENT OFFICE.

HENRY F. POPE, OF CLEVELAND, OHIO, ASSIGNOR TO THE NATIONAL MALLEABLE CASTINGS COMPANY, OF CLEVELAND, OHIO, A CORPORATION OF OHIO.

JOURNAL-BOX-SECURING MECHANISM.

1,024,456.

Specification of Letters Patent. Patented Apr. 23, 1912.

Application filed January 3, 1912. Serial No. 669,189.

To all whom it may concern:

Be it known that I, HENRY F. POPE, of Cleveland, Cuyahoga county, Ohio, have invented a new and useful Improvement in 5 Journal-Box-Securing Mechanism, of which the following is a full, clear, and exact description, reference being had to the accompanying drawings, forming part of this specification, in which—

10 Figure 1 is a side elevation showing a portion of a side frame with a journal box having my improved retainer; and Figs. 2 and 3 are respectively side and end elevations of the lower portion of the box showing 15 the hook shape of the movable retainer.

My invention relates to securing devices 20 for journal boxes on car trucks, such as shown in the patent of J. J. Byers, No. 996,000, dated June 20th, 1911. In the 25 structure shown in that patent, the bolt or similar securing device is threaded through an eye retainer at the bottom of the journal box. With such holders it will be necessary, in removing the journal box, to jack 30 up the side frame until the upper end of the securing device is below the ledge of the side frame over the journal box. As this distance is several inches, the device of 35 said patent is somewhat objectionable, and my invention is designed to overcome this difficulty and reduce the requisite amount of jacking up in order to remove the journal box or insert a new one.

To that end, my invention consists in 40 providing a movable retainer, which has means for normally holding it in retaining position, but may be moved out of the way when desired. In the preferred form, the retainer is in the form of a swinging hook 45 having a counterweight which normally holds it under the securing bolt or strap and in position to engage and retain this strap in operative position if the nut should work loose or be lost.

45 In the drawings, 2 designates a side frame of the car truck having at its end an overhung extension 3 with depending rib or lip 4, to receive the journal box 5. The box fits against the horizontal bearing 50 face 6, and a vertical bearing face 7, substantially at right angles thereto, and is held by a strap bolt 8. This strap bolt fits within a suitable grooved recess 9 in the box, its lower end having a head 10 which 55 may be slid up through a slot in the side

frame, the head engaging the rib at the side of the slot. The upper end of the bolt is threaded at 11 to receive a nut 12.

As the nut might through carelessness in assembling, become loose or work off, it is 60 desirable to provide a retainer; and to avoid the disadvantage of the retainer shown in the Byers patent above referred to, I provide a movable retainer, which is normally held in position to support the securing bolt 65 in case the latter becomes loose through breakage or loss of the nut, but may be moved out of position. In the form shown, this takes the form of a hook 13, pivoted between depending lugs 14 on the journal 70 box and having a counterweight 15, which normally holds the hook opening underneath the securing bolt. In case the nut becomes loose, or works off, the bolt would drop into the hook retainer and remain in 75 operative position and be held against dropping on the track. In case it is desired to remove the box, the nut is unscrewed, the retainer swung to one side, and the securing bolt dropped straight down 80 and out of its bearings.

The advantages of my invention result from the use of the movable retainer, which is normally held in retaining position, but may be moved out of position temporarily 85 in case the securing bolt is to be removed.

Many changes may be made in the form and arrangement of the box, the securing device, the retainer, &c., without departing from my invention. 90

I claim:—

1. A removable journal box for car axles, a securing device therefor, and a movable retainer attached to the journal box and arranged to normally rest below but in position to support the retaining device in case of its becoming loosened; substantially as described. 95

2. A journal box for car axles arranged to be held in place by a securing device extending beneath the box, and a removable retainer attached to the box and having means for normally holding it below the securing device and in position to support the securing device in case it becomes 100 loosened, substantially as described.

3. A journal box for car axles arranged to be held in place by a securing device and a retainer pivoted to the bottom of the box and having means for normally holding it 105 110

- in position below the securing device and in position to hold the securing device in case of its loosening; substantially as described.
5. A journal box having a hook-retainer pivoted to its lower portion and provided with a counterweight arranged to normally hold the retainer in operative position; substantially as described.
10. 5. In a car truck, a side frame having a seat for a journal box open at one side and the bottom, and a strap or bolt securing the box to the side frame, said box having a movable retainer in its lower portion which is normally held in operative position underneath the strap or bolt; substantially as described.
15. 6. In a car truck, a side frame having a
- journal box seat and a retaining strap or bolt securing the journal box in place, said box having a pivoted hook-retainer underneath the securing bolt, with means for normally holding the hook in operative position; substantially as described.
7. A journal box for car axles having a removable retainer attached to its lower portion in position to extend beneath and support a securing device if the same becomes loosened; substantially as described.

In testimony whereof, I have hereunto set my hand.

HENRY F. POPE.
